J.C. Robie,

Railroad Turn Table,

No 11,532,

Patented Aug. 15, 1854.

UNITED STATES PATENT OFFICE.

JACOB C. ROBIE, OF BINGHAMTON, NEW YORK.

TURN-TABLE.

Specification forming part of Letters Patent No. 11,532, dated August 15, 1854; Reissued May 5, 1857, No. 460.

To all whom it may concern:

Be it known that I, JACOB C. ROBIE, of Binghamton, in the county of Broome and State of New York, have invented certain new and useful Improvements in Turn-Tables for Railroads; and I do hereby declare that the following is a full, clear, and exact description of the same, reference being had to the accompanying drawings, 10 forming part of this specification, in which—

Figures 1, and 2 are longitudinal vertical sections through the center of a turn-table, constructed according to my invention. Fig. 15 3, is a plan of the same. Fig. 4, is a transverse vertical section, nearly in the center. Fig. 5, is a plan of the top roller plate. Fig. 6, is a plan of the bottom roller plate and the rollers, the top roller plate being 20 removed to show them.

Similar letters of reference indicate corresponding parts in the several figures.

The object of this invention is to construct a turn-table which shall possess the same 25 strength and stability as the turn-tables in common use, but may be constructed at a less cost; and which will require a comparatively small, and therefore, less costly foundation.

30 The invention consists in balancing the platform of the turn-table upon the revolving roller carriage which supports it, in such a manner that, either end of the said platform may be depressed to rest upon a bed or bearing provided for it, while it receives, or has discharged from it, an engine and tender, or any car, and in furnishing the turn-table between the roller carriage and platform, on opposite sides of the center, 35 with eccentrics which are so arranged, and can be so operated as to support the platform on a level previous to turning it, and holding it steady in such position during its revolution; or, to raise one end and depress 40 the other, upon its bearings, when it is desired to receive or discharge the engine and tender, or car.

It also consists in furnishing the turn-table with an indicator, which will show the 45 engine driver, or any other person, when the platform is exactly on a level, or in which direction it inclines, and thereby serve as a guide by which to move the engine and tender, or car, upon the platform, to such 55 a position as to hold the platform in equipoise, or on a level.

The platform of this turn-table is constructed in a similar manner to that of some others now in use, being composed of longitudinal timbers, A, A, and ties or sills, 60 B, B, which are secured below them, by bolts, a, a, and plates, b, b, running longitudinally under the sills. The sills form the floor upon which the rails, e, e, are laid. The platform is stayed to prevent deflection, by 65 tension rods, c, c, which are attached to ears, d, d, which stand up from the plates, b, b, on either side of the longitudinal timbers, and to pillars, C, C, which are erected upon the longitudinal timbers near the center. It is further strengthened at the center; by short longitudinal timbers, D, D, which are bolted under the timbers, A, A, and sills, 70 B, B.

A transverse horizontal shaft, E, of iron, 75 is placed under the center of the platform, and its ends secured firmly in the longitudinal timbers forming the sides of the platform. The platform forms a balance, of which this shaft is the axis. The shaft is 80 supported along the whole of its length between the sides of the platform, or at suitable intervals in a bearing, F, running across the center or axis of the roller carriage, and it supports two bearings, G, G, 85 for the rails, e, e.

The roller carriage consists of the bottom and top plates, H, H'; a center pin, J; the two rings, I, I'; the rollers, K, K; and their axles, f, f. The bottom and top plates 90 in a turn-table of the largest size to carry an engine and tender, say from forty (40) to forty five (45) feet in length or diameter, will not require to be of more than eight (8) feet in diameter. The bottom plate, H, has 95 two circular raised tracks, g, g, and is bored to receive the center pin, J. It rests upon a foundation of masonry about three (3) feet below the level of the rails, e, e. This foundation will be very small, compared 100 with the foundation of the track usually provided for rollers near the ends or outside of the table. The rollers, K, K, are fitted loosely upon their axles, f, f, with a collar, h, between each pair; and the axles support the two rings, I, I', which keep 105 them at proper distances from a common vertical axis to run on the tracks, g, g, and keep the several pairs at proper distances from each other. The inner ring, I', is connected with a central plate, L, which is bored through the center for the center 110

pin, *J*, to pass through, and keep the two rings concentric with the axis on which the table rotates; or, instead of having the central plate, the ring, *I'*, may be connected by 5 arms with a hub. The top plate, *H'*, is of the same size as the bottom plate, *H*, and has two similar circular tracks, *g*, *g*, on its under side, which rest upon the rollers. The center pin, *J*, is firmly secured by keying 10 or otherwise, to the top plate, *H'*, and passes through the plate, *L*, and the bottom plate, *H*; the latter having a deep hub, *i*, in order to give the pin a deep guide. The bearing, *F*, for the shaft, *E*, of the platform, rests 15 upon, and is secured by bolts, or other means, to the top plate, *H'*, and is so placed, that the axis of the center pin, if continued upwards, would cut the axis of the shaft, *E*.

At equal distances from and parallel with 20 the shaft, *E*, on opposite sides of it, are two shafts, *M*, *M'*, whose ends have journals, which are fitted to work in bearings secured to metal plates, *k*, *k*, which are attached to the sides of the platform. The central 25 portion of each of these shafts, for so much of their length as is included between *l*, *l*, and shown in dotted lines in Fig. 3, is larger than the other portion, and made eccentric to the journals, as 30 shown in Figs. 1, and 2, where the section is taken through the eccentric portion, and the journals are shown by dotted circles. Upon the top side of the upper roller plate, *H'*, there are two raised pieces, *m*, *m*, which 35 form bearings for the eccentric portions of the shafts, *M*, *M'*, to rest upon. Each of the shafts, *M*, *M'*, is furnished, outside the platform, with a lever, *n*, by which it can be turned to bring that side of the eccentric 40 portion which is farthest from its axis, undermost, as shown at *M*, in Fig. 1, and thus coming in contact with its bearing, *m*, on the top roller plate, elevate that end of the platform which is on the same side of the 45 shaft, *E*; or, it can be turned to such a position, as shown at *M'*, in the same figure, that it will not, when that end of the platform on the same side of the shaft, *E*, is depressed to its lowest position, touch the 50 bearing on the roller plate.

The depressed end of the platform always rests upon bearing pieces, *N*, *N*, of which, two are provided to receive either end in all the positions the turn-table is 55 required to assume. These bearings may consist of heavy timbers resting upon foundations of masonry, or may be constructed in any other suitable manner; and they should be so placed as to support the platform under the rails. The object of these 60 is to obviate all lateral strain upon the roller, or center pin, when the platform receives its load. The drawing represents, in Fig. 3, two sets of these bearings—one 65 set being shown in perfect outline, and the

other set, in dotted outline, supposed to be seen through the platform; the two sets being arranged to bring the turn-table in line with rail tracks at right angles with each other, and either set serving for two positions of the turn-table, the reverse of each other. 70

The turn-table is caused to rotate, in a well known way, by means of a pinion, *o*, which is secured on a vertical shaft, *p*, attached to the platform, and gears with a circular toothed rack, *q*, which is secured to the foundation work. 75

The indicator, which shows when the platform is exactly in equipoise, or on a level, 80 consists of an index pointer, *r*, whose horizontal arbor works in suitable bearings in a box, *R*, which is supported by a pillar, *Q*, standing on one side of the platform. The axis of this arbor stands in an imaginary 85 line, which is perpendicular to the platform, and passes through the axis of the shaft, *E*. The arbor carries a small toothed wheel, *S*, (shown dotted in Figs. 1, and 2,) which gears with a toothed sector, *t*, on the top of 90 a small pillar, *P*, which is erected on a standard, *T*, secured to the top roller plate, *H'*. The toothed sector is described from the axis of the shaft, *E*, so that as the platform oscillates, it always remains in gear with the wheel, and turns the arbor, and moves the index. The index is so adjusted, 95 that when the platform is on a level, it stands in a vertical position; but, when the platform is not on a level, it will point toward the highest end, and thus show the way in which it is necessary to move the engine or carriage, in order to bring the platform to a state of equipoise. 100

When an engine or car is to be run on the turn-table, the shaft, *M*, or *M'*, which is nearest the end where the engine or car is to be run on, is turned by its lever to such a position, that the eccentric part cannot touch its bearing, *m*, on the top roller plate, *H'*, as indicated at *M'*. The other shaft is turned to bring the eccentric part in contact with its bearing, *m*, and raise the other end of the table, until the first named end is depressed far enough to rest on the bearing pieces, *N*, *N*; and in this position, indicated at, *M*, in Fig. 1, it is allowed to remain until the engine or car is run on the table, when it is moved to a position corresponding to that of the shaft, *M'*, in the same figure, to allow the platform to be balanced. When the engine or car is brought to the proper position to bring the platform to a state of equipoise, the two shafts, *M*, and *M'*, are moved to the positions shown in Fig. 2, to bring their eccentric portions into contact with the bearings, *m*, on the top of the roller plate, and thus give support to the platform on opposite sides of the shaft, *E*. The turn-table 115 120 125 130

may then be turned in any direction. When it is desired to run off the engine or car, the support of the eccentric on that side of the shaft, E, from which it is to be run off, is removed by turning the shaft, M, or M', to such a position, that the eccentric cannot touch its bearing, m, which leaves that end of the platform free to fall, when the load is moved toward it.

10 The rails, m, of the turn-table, and the rails of the track are so arranged relatively to each other, that the depressed ends of the former are always at the same level as the latter, and will bear on their chairs when the platform rests on the bearing pieces, N, N. The distance of the oscillation of the platform is somewhat exaggerated in Figs. 1, and 2, in order to make the operation more clearly intelligible by the drawings.

20 The actual distance of the oscillation of the ends of the platform, from their positions when in equipoise, need not be more than three quarters of an inch, or an inch, in a full sized turn-table, as it is only necessary that the ends of the table rise far enough from the bearing pieces, N, N, to enable them to swing perfectly free, without any danger of contact.

25 What I claim as new and useful, and desire to secure by Letters Patent, is—

1. Balancing the platform of the turn-table upon a transverse central shaft (E) or other suitable axis resting upon the roller carriage in a line intersecting the line of the axis upon which the turn-table rotates, 35 in such a manner that, the table, when in a horizontal position, is elevated or has its rails above those of the track, to admit of the free swing of the table over its under supports or bearings (N), and so that, the 40 table may be rocked with facility from its center or tilted to bring the ends of its rails on either side of the balancing shaft into line or level with the rails of the track substantially as and for the purposes herein 45 set forth.

2. I also claim the manner herein described of holding the table steady at its horizontal set while rotating, and tilting or depressing it on either side of the balancing axle (E) when required, by means of the cams (M M') arranged to bear upon the roller carriage and operating in connection with the roller carriage and table as herein set forth.

JACOB C. ROBIE.
